UNITED STATES PATENT OFFICE.

AUGUST KEHM, OF CHICAGO, ILLINOIS.

RADIATOR.

Application filed January 3, 1920. Serial No. 349,136.

To all whom it may concern:

Be it known that I, AUGUST KEHM, a citizen of the United States, and resident of Chicago, county of Cook, and State of Illinois, have invented certain new and useful Improvements in Radiators, of which the following is a specification, and which are illustrated in the accompanying drawings forming a part thereof.

10 The invention relates to radiators and has for its object to improve their appearance and efficiency, to effect a more uniform distribution of heat throughout the rooms which they serve and to prevent the local 15 discoloration of walls or ceilings by the continued contact therewith of currents of warm air over relatively small areas. In the great majority of installations, radiators are most conveniently located near the walls 20 or windows. Unless some form of shield or deflector is employed, the upward movement of the heated air about the radiator results in an objectionable accumulation of dirt on the adjacent wall or window and upon the 25 ceiling.

While a shield or deflector may be employed to reduce the accumulation of dirt upon the adjacent wall above a radiator, these devices are unsightly and their use results 30 in a substantial reduction in the velocity of the air movement over the heated surfaces of the radiator. This so reduces the efficiency of the radiator that it has been the practice to increase the size of the radiator for a given installation when it is known 35 that a shield or deflector is to be used.

The loss of efficiency resulting from the use of shields or deflectors is believed to be principally due to the fact that, as heretofore constructed, these devices remain relatively cool in service. While they are located near the radiator, they are warmed only by radiation and convection whereby the temperature which they attain is only 45 substantially that of the room, as distinguished from that of the heated parts of the radiator. The effect of the shield is therefore to retard the upward movement of the air which comes in contact with its relatively cool surfaces.

The present invention accordingly contemplates an arrangement whereby the rising air is not only diverted away from the adjacent wall or window by walls which 50 have substantially the same temperature as the heated parts of the radiator, but which

also serve to confine the air in its travel over the heated surfaces until the maximum temperature is attained. A greater velocity of air movement thus results and increased efficiency is secured, frequently to such an extent that the columns or loops of the radiator may be more widely separated than has heretofore been customary without enlarging the overall dimensions of a radiator of 60 predetermined heating capacity because of the reduced amount of heating surface required. Not only is more space thus provided for the movement of air upwardly between the coils but a much less amount of 70 the heating fluid is required to fill the radiator, and this is of great importance when hot water is used as the heating medium. By the use of such radiators the total amount of 75 water in a given system is reduced and a more prompt response to changes in the condition of the fire is insured.

This application is in part a continuation of my application for patent on radiator, Serial No. 184,065 filed August 2, 1917, and 80 allowed July 3d, 1919.

In the accompanying drawings:—

Fig. 1 is a front elevation showing one form of radiator embodying the features of improvement provided by the invention, 85 some parts being broken away;

Fig. 2 is a transverse sectional view of the same;

Fig. 3 is a plan sectional view taken on the line 3—3 of Fig. 1;

Figs. 4, 5 and 6 are detail perspective views showing the covering plates which may be used in the construction of the radiator;

Figs. 7 and 8 are similar to Figs. 1 and 2 95 respectively, but show a different style of radiator; and

Fig. 9 is a detail plan sectional view showing another form of construction.

When the radiator is to rest upon the floor 100 of the room, near a wall or window, one of the two forms of construction illustrated in Figs. 1, 2 and 3 and in Fig. 9 may be used. In either case the radiator will usually comprise a series of upright loops, as 10, 11, or 105 12, 13, arranged side by side with intervening air spaces, as 14, (Figs. 1 and 3) or 15 (Fig. 9). Each of the loops 10, 11, and 12, 13, comprises a plurality of chambered columns, three columns, as 16, 17, and 42 being 110 shown in Figs. 1, 2 and 3 and two columns 18, 19 being shown in Fig. 9. In the illus-

trated constructions, these columns are connected only at the top and bottom of the air loops. Under these circumstances, the air spaces 14 or 15, between the loops are connected throughout the greater portion of their length by air spaces, 20 or 21, located between the columns of the several loops. When steam is to be employed as the heating fluid, connecting nipples, as 22, are provided only at the lower ends of the loops. The intervening air spaces, as 14 or 15, accordingly extend to the full height of the loops.

In the form of construction illustrated in Figs. 1 to 6 inclusive, the heated walls for confining and directing the air currents are provided by the use of separately applied plates, 23, 24, 25 and 43. As each of these plates is relatively narrow and makes close contact with the radiator loops along both of its margins, throughout the entire length of the plate, the plates are sufficiently heated by conduction to become a part of the effective heating surface of the radiator. The plates 23 are applied to ends of the radiator. These plates accordingly serve to close the air spaces 20 between the adjacent columns 16, 42 and 17, 42, of the terminal loops, as 10 (Fig. 3).

The plates 24 are of less length than the height of the radiator and are formed with openings 27 in their upper portions whereby they serve to cover the air spaces 14 at the front of the radiator, but only in the intermediate height of the same. Openings 28 are accordingly provided below the plates 24 for the admission of air at the lower front portion of the radiator and this air, after being heated during its upward travel through the air spaces 14 of the radiator, is discharged in a substantially horizontal forward direction through the openings 27 in the upper portions of the plates 24. Owing to the relatively wide separation of the radiator columns or loops 10, 11, ample room is provided for the movement and heating of large volumes of air.

The plates 25 extend nearly the full height of the radiator at the back and connect with the plates 43 which extend over the top of the same to the upper ends of the plates 24 above the openings 27. The plates 25 and 43, like the plates 24, are of suitable width to cover the air spaces 14 between adjacent columns, as 10, 11. The several plates 24, 25 and 42 accordingly cooperate to confine the air currents within the air spaces 14 and 20 in the intermediate height of the radiator and to discharge the heated air outwardly into the room away from the adjacent wall or window.

Clamping bolts 30 and 31 serve for securing the plates 23, 24, and 25 in place. As shown, the clamping bolts 30 extend through the plates 23 and through suitable anchor

plates, as 32, which bridge the space between the columns 16, 42 or 17, 42, of the corresponding radiator loop, as 10, upon the inside of the same. The clamping bolts 31, on the other hand, extend continuously through the plates 24 and 25. In each case the clamping bolts should be sufficiently numerous to insure a firm engagement of the margins of the corresponding plates with the radiator loops, throughout the entire length of the plates. While the plates 23, 24, 25 and 43 will usually be formed of metal, they may be produced from a special plastic composition of relatively high heat conducting quality, when ornamentation of the plates is particularly desired. As shown the plates 24, 25, and 43 are formed of thin cast metal with ornamented exterior surfaces and the adjacent ends of the plates 24, 43 and 25, 43 are rabbeted and united with clamping bolts 44 (Fig. 2). If desired one of the plates 24 may be so formed as to provide a well 45 extending inwardly therefrom between the adjacent loops of the radiator, the upper end of the well being preferably just below the level of the lower margin of the corresponding opening 27. The well 45 may thus be filled with water through the opening 27 for humidifying the atmosphere of the room in which the radiator is used.

The radiator illustrated in Fig. 9 is constructed to confine and direct the ascending air currents in the same manner as the radiator illustrated in Figs. 1, 2 and 3. In this instance, however, the cover plates for the intervening air spaces 15 and 21 are formed by providing the radiator loops 12, 13, with integral meeting marginal flanges 33, 34, the terminal loops, as 12, being each also formed with an integral web 35, between the columns 18, 19. Under these circumstances, the flanges 33 and 34 and the webs 35 have true conducting heating surfaces, whereas in the form of construction illustrated in Figs. 1, 2 and 3, the plates 23, 24 and 25 have only what is known as contact surface.

Figs. 7 and 8 illustrate a type of wall radiator forming the subject of my applications for mechanical and design patents Serial No. 154,349, and Serial No. 154,413 filed March 12th, 1917. As the columns 36 of this radiator are connected at top and bottom by tubular headers 37, which extend throughout the length of the radiator, flat plates 38 and 39, applied to the front and back of the radiator, are sufficient to secure the desired result in confining and diverting the ascending air currents. Each of the plates 38 and 39 is of suitable width to make close contact at its opposite margins with two adjacent columns 36 of the radiator and to form a cover for the intervening air space, as 40. As in the form of construction illustrated in Figs. 7 and 8, the plates 38, which are ap-

plied at the front of the radiator are of such length as to extend only in the intermediate height of the radiator, while the plates 39 which are applied at the back of the radiator 5 extend throughout the full height except for a short distance adjacent its lower edge. The plates 38 and 39 are held in place by clamping bolts 41 which extend continuously through the corresponding plates of both 10 sets.

The offset columns 36 of the wall radiator forming the subject of my said applications for design and mechanical patents are peculiarly adapted for diverting the ascending 15 air currents outwardly away from the adjacent wall or window in the manner provided by the present invention although the present invention is not limited in its application to this particular type of wall radiator. As the plates 23, 24, 25, illustrated in Figs. 1, 2, and 3, the webs and flanges 33, 34, 20 35, (Fig. 9) and the plates 38 and 39 (Figs. 7 and 8) have substantially the same temperature as other parts of the radiator, they assist 25 in effecting, rather than result in retarding, the upward movement of the air currents. Furthermore, the air is so confined that it is required to travel over the heated surfaces for a substantial distance and a high 30 temperature is attained. An increased velocity of the ascending air currents thereby results and this not only serves to render the radiator more efficient but it also serves to effect a more uniform distribution of the air 35 throughout the room as it is discharged outwardly away from the wall in the upper portion of the radiator. There are accordingly no local accumulations of dirt upon the walls or ceilings and the radiators are not 40 required to be of increased size, although they may contain a less number of columns or loops.

I claim as my invention:

1. A radiator comprising, in combination, 45 a series of upright heating columns arranged side by side with intervening air

spaces, and two sets of upright wall plates each having close contact at its opposite edges throughout its entire length with the outer edge of two adjacent columns, the plates of one set covering the said intervening air spaces throughout a substantial distance in the intermediate heights only of the radiator at one side of the same, but not covering air spaces adjacent the top and bottom of the radiator, and the plates of the other set extending from a point adjacent the bottom of the radiator at the other side of the same to and over the top of the radiator. 50 55

2. A radiator comprising, in combination, a series of upright heating columns arranged side by side with intervening air spaces and heat conducting walls making close contact with the outer margins of the columns and covering the intervening air spaces throughout a substantial vertical distance in the intermediate height only of the radiator at the front side of the same, but leaving uncovered air spaces adjacent the top and bottom of the radiator at the front side of the same, 70 and closing the air spaces at the back of the radiator to a point adjacent the bottom thereof whereby air entering at the lower portion of said radiator will be directed upwardly along said columns and laterally outwardly 75 from a point adjacent to the upper portion of said radiator for heating and circulating the air in the space occupied by said radiator.

3. A radiator comprising, in combination, 80 a series of upright columns arranged side by side, with intervening air spaces, two sets of upright wall plates located on opposite sides of the radiator, each plate having close contact at its opposite edges with the adjacent outer edges of two adjacent columns, and one of said plates having a water well 85 associated therewith which extends inwardly from said plate between the adjacent columns of the radiator.

AUGUST KEHM.
